UNITED STATES PATENT OFFICE

156,227

DESIGN FOR A COMBINED ARTIFICIAL FIREPLACE, PRACTICE KEYBOARD, AND STOOL

Philip J. Gannuscio, Brooklyn, N. Y.

Application February 17, 1948, Serial No. 144,540

Term of patent 14 years

(Cl. D13—5)

To all whom it may concern:

Be it known that Philip J. Gannuscio, a citizen of the United States of America, residing at Brooklyn, in the county of Kings and State of New York, has invented a new, original, and ornamental Design for a Combined Artificial Fireplace, Practice Keyboard, and Stool, of which the following is a specification, reference being had to the accompanying drawing, forming part thereof.

Fig. 1 is a front perspective view of a combined artificial fireplace, practice keyboard and stool in a closed position, showing my new design; and

Fig. 2 is a front perspective view showing the combined artificial fireplace, practice keyboard and stool in an open position.

The back of the piano fireplace is substantially plain.

I claim:

The ornamental design for a combined artificial fireplace, practice keyboard, and stool, as shown and described.

PHILIP J. GANNUSCIO.
